[57] CLAIM

The ornamental design for a hydro-therapy nozzle for hydro-therapy spas, as shown and described.

DESCRIPTION

FIG. 1 is a perspective view taken from the top, front and left side of a hydro-therapy nozzle for hydro-therapy spas showing my new design;

FIG. 2 is a perspective view taken from the bottom, rear and right side thereof; and

FIG. 3 is a cross sectional view taken on line 3—3
FIG. 1.

The fragmentary broken line representation of a spa
wall in FIG. 3 is for purposes of illustration only.
